(57) **CLAIM**

The ornamental design for a dragonfly with prop tail, as shown and described herein.

DESCRIPTION

FIG. 1. Is a left side elevational view thereof of my dragonfly with prop tail with the right side being a mirror image view thereof;

FIG. 2. Is a front elevational view thereof;

FIG. 3. Is rear elevational thereof;

FIG. 4. Is top plan view thereof; and,

FIG. 5. Is a bottom plan view thereof.

The broken lines adjacent the shaded portion of the figure's thorax in FIG. 1 define the bounds of the claim. The broken lines showing the top surface of the thorax are for illustrative purposes only. None of the broken lines form part of the design being claimed.
